(57) **CLAIM**

The ornamental design for a hydrogen rich water generator, as shown and described.

DESCRIPTION

FIG. 1 is a perspective view of a hydrogen rich water generator;

FIG. 2 is a front view of the hydrogen rich water generator; FIG. 3 is a rear view of the hydrogen rich water generator; FIG. 4 is a left side view of the hydrogen rich water generator;

FIG. 5 is a right side view of the hydrogen rich water generator;

FIG. 6 is a top view of the hydrogen rich water generator; and,

FIG. 7 is a bottom view of the hydrogen rich water generator.
